UNITED STATES PATENT OFFICE.

JOHN P. NEFF, OF BROOKLYN, NEW YORK, ASSIGNOR, BY MESNE ASSIGNMENTS, TO AMERICAN ARCH COMPANY, OF NEW YORK, N. Y., A CORPORATION OF DELAWARE.

ARCH-BRICK AND SUPPORTING MEANS THEREFOR.

1,138,036.

Specification of Letters Patent.

Patented May 4, 1915.

Application filed January 10, 1912. Serial No. 670,403.

To all whom it may concern:

Be it known that I, JOHN P. NEFF, a citizen of the United States, residing at Brooklyn, in the county of Kings and State 5 of New York, have invented certain new and useful Improvements in Arch-Brick and Supporting Means Therefor, of which the following is a specification.

This invention has reference to certain improvements in arch bricks and a support therefor and is particularly applicable to the construction as used in a locomotive fire box. The first of the objects of my invention is the provision of a new means for supporting 10 the arch brick at the end which is adjacent the side sheet of the locomotive fire box, which improved means will afford a more stable support than has heretofore been used, and will also provide more effectively for 15 any expansion and contraction which may take place, and will in general provide an arch which will give a maximum of service at a minimum of cost.

The above, as well as such other objects 25 as may hereinafter appear I attain by means of a construction which I have illustrated in preferred form in the accompanying drawings wherein Figure 1 is a plan view showing a couple of arch bricks in place resting 30 upon a couple of tubes with one of the bricks bearing at one end upon a supporting lug carried from the inner side sheet of the fire box; Fig. 2 is a view partly in section taken on the line II—II of Fig. 1; Fig. 3 is an enlarged sectional view of the improved form 35 of lug device which I employ as the supporting means adjacent the side sheet, and Fig. 4 is an inner face view of the lug or supporting member proper.

40 Referring now more particularly to Figure 1, it will be seen that I have therein shown two supporting tubes 5 and 6 and a portion of the inner side sheet 7 of the fire box with bricks resting in position (indicated at 8 and 45 9), the brick 9 being formed to fit the tube 6 as shown at 10 and being supported at that end which is adjacent the sheet 7 by means of a casting or lug 11, the bearing or surface of the brick where it rests upon the lug 11 being inclined substantially as shown at 12 and made so that it will be somewhat out of contact with the side sheet normally whereby when expansion or contraction occurs or 50 there is a shift in the position of the tube 10, or where for any cause a movement of the

edge of the brick toward or from the side sheet occurs, it may slide up or down upon the lug 11 in a manner that will be clear from examination of Fig. 2, and this will serve to compensate for such movement. 60

As a support for the lug or casting 11, I screw into the side sheet 7, as indicated in Fig. 3, a stud 13 having preferably a squared head as shown, so arranged as to engage or interlock with the recess formed within the lug 11, the aperture being made as indicated at 14 in Fig. 4 and constructed so that the lug will be driven into tight contact with the side sheet by a downward pressure of the inclination of the face 15 which engages the 70 inner side of the head of the stud on both sides.

By the arrangement shown the lug 11 serves to protect the stud 13 from the action of the heat, and if the lug 11 becomes damaged or burned, it can be replaced without the necessity of replacing the stud 13 and the replacement can be effected by the arrangement shown with a minimum of expense and trouble. The lug or casting 11 is 75 preferably made substantially of the shape shown, particularly in Figs. 3 and 4, and should be made of a size sufficiently small so as to not interfere with access to the stay bolts in the fire box. 80

It will be noted that the intermediate brick 8 is made of substantially like shape to the brick 9, it being found that this arrangement avoids locking of the brick due to distortion of the arch tubes. 85

If the brick to be supported is of large size it may be desirable in some cases to use more than one supporting lug for each brick but ordinarily I prefer to employ but one such lug placed near the middle of the end 90 edge of the brick with the adjacent portions of the edge receding or inclined away from the side sheet in the manner shown in Fig. 1 whereby there is compensation for change of angularity as between the side sheet and 100 the supporting tube that carries the opposite end of the brick.

In forming the arc socket at the one end of the brick, I make the arc of the same a little less than 90 degrees which allows a 105 certain clearance between adjacent bricks, as indicated above the tube 6. It will be obvious that by making the angle of the brick at 12 to incline at a proper degree, I avoid all wedging, binding or holding action as 110

- between the brick and its supports and also any tendency to springing of the tubes. By the arrangement shown I am enabled to secure as much as one inch variation of distance between the supporting elements for any given length of arch unit without changing the nature of the bearing upon the supporting elements and without interfering in any wise with the general arrangement.
- 10 This application is subsidiary to my earlier application Serial No. 649,219, filed September 11th, 1911, in matter of the invertibility of the arch brick; and is subsidiary to the Charles B. Moore application Serial No. 666,345, filed December 18, 1911, in matter of the compensating wedging action of the bricks.

Having thus described my invention and illustrated its use, what I claim as new and desire to secure by Letters Patent is the following:

1. In a locomotive fire-box, an arch brick having an inclined surface and a socket at opposite ends of its upper face and an inclined face and socket at opposite ends of its lower face, the length of the upper face being different from that of the lower face to accommodate the brick to arch-supporting members which are differently spaced apart.

2. In a locomotive fire-box, an arch brick having an inclined surface and a socket at opposite ends of its upper face and an inclined face and socket at opposite ends of its lower face, the length of the upper face being different from that of the lower face to accommodate the brick to arch-supporting members which are differently spaced

apart, and the said inclined surfaces being adapted to rest upon and project laterally above an arch-supporting member for compensating engagement therewith.

3. In a locomotive boiler fire box, a group of arch tubes and the side sheets of said box, in combination with a refractory arch body resting upon said tubes, a plurality of edge bricks, each resting upon one said tube, and extending toward but not against the adjacent side sheet, and each having a bottom end portion inclined with respect to the bottom of the brick, and edge brick supports wherewith the inclined end portions of the edge bricks compensatingly engage immediately adjacent respective side sheets.

4. The herein described improvement in locomotive firebox arches, comprising an arch brick the lower part of which is shorter than the space between its supports while its upper part is of a length to overhang both such supports, one end of said brick being shaped for pivotal abutment with several points upon one said support and its other end having an inclined point or edge for compensating wedging abutment with one point upon the other support whereby the brick is adapted to adjust itself to such supports and retain its position thereon and whereby an arching effect is secured in the intermediate parts of the brick.

In testimony whereof I have hereunto signed my name in the presence of the two subscribed witnesses.

JOHN P. NEFF.
